(57) **CLAIM**

I claim the ornamental design for a modular distributor for air conditioning systems, substantially as shown and described.

DESCRIPTION

FIG. 1 is a top view of the modular distributor for air conditioning systems, showing its new design; FIG. 2 is a side view thereof (each of the two sides being identical in design);

FIG. 3 is an end view thereof (each of the two ends being identical in design); and,

FIG. 4 is a perspective view showing an end and side thereof.
